Attorney

UNITED STATES PATENT OFFICE.

CHARLES F. MILLER, OF COLUMBUS, OHIO.

STOOL.

1,398,935.

Specification of Letters Patent. Patented Nov. 29, 1921.

Application filed April 29, 1921. Serial No. 465,438.

To all whom it may concern:

Be it known that CHARLES F. MILLER, a citizen of the United States, residing at Columbus, in the county of Franklin and State 5 of Ohio, has invented certain new and useful Improvements in Stools, of which the following is a specification.

This invention relates to improvements in resilient stools, and has for its primary object to provide a stool of this character which is adapted for use upon street cars or other moving vehicles for enabling the operators thereof to remain comfortably seated while controlling the vehicles, this object 15 being carried out by the provision of an improved spring structure for such stools which serves to absorb the vibration and jar imparted to the vehicle and to thereby prevent the jolts and jars from interfering 20 with the comfort of the operator.

The present invention consists in the provision of a stool wherein is embodied a rigid frame, a seat, a stem depending from the seat and an improved spring structure between the frame and stem for the purpose of resiliently supporting the seat, the said spring structure including radially extending springs which are adapted to be connected with the frame and with collars 30 loosely mounted upon the stem, and said radially extending springs being supplemented by a plurality of vertically disposed springs, which connect the lowermost of said collars with the upper part of said frame 35 and serve to resiliently support the seat when the latter is occupied.

Another object of the invention resides in improving the construction of the stool disclosed in the copending application of Albert Miller *et al*, Serial Number 339,363, filed November 20, 1919, which application the present applicant is an assignee of the title thereof.

In the accompanying drawing:

Figure 1 is a side elevation of the springs 45 comprising the present invention,

Fig. 2 is a vertical longitudinal sectional view taken through the stool, and

Fig. 3 is a horizontal sectional view taken 50 along the line 3—3 of Fig. 1.

Referring more particularly to the details of the invention, the numeral 1 designates my improved stool in its entirety, as shown, the stool consists in this instance of a metallic frame 2, which may be formed from

substantially vertically disposed angle bars 3, which are united by means of rigid cross bars 4. This construction serves to render the frame substantial in construction, capable of withstanding hard and severe usage 60 and at the same time permits the same to be relatively light in weight so as to be readily handled.

The stool further includes a seat 5, of any suitable design or construction, in the 65 form of the invention illustrated the seat being designed for the use of the operator of a passenger carrying vehicle, but it will be apparent that the seat may also be used in drafting rooms, in connection with book- 70 keeping offices, cashiers' desks and in very many other different occupations. The seat 5 in this instance is provided with a depending stem 6, which is rigidly secured as at 7 to the under surface of the stool, the said 75 stem being adapted to extend downwardly and vertically through the frame 2, and has its lower end threaded for a suitable distance as at 8. Arranged to be threadedly carried by the lower end 8 of the stem is a collar 9 80 that carries radially projecting arms 10, which arms have their outer ends connected with the inner ends of radially disposed springs 11. These springs are disposed to incline downwardly and outwardly, and 85 have their outer ends secured in any suitable manner to the frame 2, the said springs 11 serving to center the positions of the lower ends of the stem and also to absorb a part of the weight placed upon the seat 5. 90

However, to absorb the greater part of the weight which will be placed upon the stool, I employ substantially vertically disposed springs 12, which have their upper ends connected with the upper portion of the frame 2, 95 and have their lower ends connected with the outer ends of the arms 10 immediately adjacent to the inner ends of the springs 11. It will be manifest that by reason of this construction when weight is deposited upon the 100 seat 5, the stem will move downwardly a distance resiliently limited by the co-operative action of the springs 11 and 12. Also, carried by the upper end of the frame is a plurality of radially projecting springs 13, 105 which are situated to extend parallel with the springs 11. These springs 13 have their inner ends connected with the outer portions of radially extending arms provided upon a collar 14, the latter being loosely positioned 110

around the upper portion of the stem 6. The spring structure described serves through the instrumentality of the collar 9 to effect the resilient support of the seat structure, 5 and provides a very efficient construction for this purpose. The collar 14 is maintained in its proper position with respect to the stem 6 by providing a rebound absorbing spring 15, which surrounds the stem 6 10 and is positioned between the collars 9 and 14. It will be seen that the spring 15 by reason of its location and coöperation with the collars 9 and 13 will serve to arrest sharp upward movement on the part of the seat when 15 weight upon the latter is suddenly released or removed, and also to render the operation of the spring structure generally smooth, uniform and devoid of intermittent or jerky movements. Another feature found in the 20 present invention by the use of the horizontal springs 11 and 13 is the lateral movement which may be imparted in a limited degree to the seat. In the application above referred to the seat is only resilient with respect to the vertical, the stem being gripped in such manner as to preclude lateral movement on the part of the seat in any degree. However, it will be manifest that while the 25 springs 11 and 13 will serve normally to maintain the stem within the center of the frame, yet they do not afford the slight lateral motion mentioned, a feature which is 30

of marked advantage for the operators of common carriers.

What is claimed is:

1. A stool of the character described comprising a supporting frame, a seat, a stem depending from said seat, said stem being provided with a threaded lower portion, a member threaded to the lower portion of 40 said stem and permitting of vertical adjustment on the part of said seat, a second member loosely carried by said stem above said first named member, a rebound spring positioned between said members and serving to 45 space the latter, and a plurality of shock absorbing springs extending between said members and said supporting frame.

2. A stool of the character described comprising a supporting frame, a seat, a stem depending from said seat and arranged vertically and centrally of said frame, a member capable of threadedly receiving the lower end of said stem, a second member loosely carried by said stem above said first named 55 member, a rebound absorbing spring surrounding said stem and exerting pressure upon said members to separate the latter, and horizontal and vertical extending springs carried by said frame and having the inner 60 ends thereof connected with said members.

In testimony whereof I affix my signature.

CHARLES F. MILLER.
